UNITED STATES PATENT OFFICE

SAMUEL SISKIN, OF ELMIRA, NEW YORK

COAT

Application filed June 6, 1927. Serial No. 196,888.

This invention is directed to the production of a collared coat in which the labor producing the proper fit at the neck is greatly reduced, and by which a collar having in itself advantages, is obtained.

To this end the material of the coat body is continued upwardly at the neck to the line at which the collar folds, and the collar is applied as a single layer, preferably of the self-material of the coat, to the inside of the fabric of the coat body at the neck and folded down over the outer edge of the neck opening to the outside of the coat. This produces a collar of a single thickness and obviates the under collar commonly used. The resultant collar is therefore, relatively light, and does not need the stiffening now applied in order to hold it up. In order, however, to stay the front portions of the gore of the collar, I insert within the edge of the collar a tape located adjacent to the point of the collar following the top edge, and extending rearwardly a few inches from each point of the collar. I thus produce a collar of minimum thickness at the rear, but provided with a staying immediately at the gore.

In the drawings,—

Figure 1 is a representation of a front piece of a coat cut to embody my invention, the piece being suitable for the production of a man's coat, although it will be understood that by changing lines not essential to this invention, it may be suitable to women's wear, or coats and cloaks in general.

Figure 2 is a back half cut according to this invention.

Figure 3 is a side view of a coat embodying my invention with the collar turned up.

Figure 4 is a front view of a coat embodying my invention with the collar turned down, and

Figure 5 is an enlarged vertical section through the upper part of the coat and collar and corresponds to Figure 3 with the collar turned down.

My improved coat body proper is composed of the customary number of pieces, namely, two front pieces marked 1, and two back pieces marked 2, it being understood, of course, that the back may be composed of

a single piece as is usual when a seamless back is desired. The neck of my improved coat, however, is cut higher than is now customary, it being cut so that the material of which the parts 1 and 2 is composed, extends upwardly to the line on which the collar itself is to turn, as is represented in the lines *a-a* of Figures 1 and 2, the customary cut being shown in line *b-b* of those figures. The collar itself is made of a single piece of fabric marked 3, cut to proper shape and having one edge sewed around the neck opening of the coat on the inside thereof, it being folded over the top edge of the neck opening left in the pieces 1 and 2. Its free edge may be, as shown at 4, in Figure 5, turned in under, to provide the necessary finish.

It will be seen that by this construction, the collar proper is composed of a single thickness, and that no under collar is used. This renders the collar very thin and light, and permits it to be held up by the stiffness of the body portion of the coat itself, and for this purpose it is desirable, as shown to work inside of the neck of the pieces 1 and 2 proper stiffening material, extending up to the fold line in the rear, and sloping toward the front. This is shown at 5 in Figure 5. This serves as a reinforcement.

As a result, I have obtained a collar which is flexible, and which may be easily constrained to follow the desired contour lines of the neck, and this is assured by extending a strip of tape or a stay of a proper material represented at 6, in Figure 3, along the top edges of the neck opening of the pieces 1 and 2 of the coat, and extending down along the lapel front line of the side and front pieces, and along the edges of the coat, whereby the weight of the skirts of the coat are transmitted directly around the neck and to the back of the coat at the neck opening. This tape may be taken up by pleats within the lining at about the point represented at 7, which is about opposite the gore of the collar. If the coat material is cut high forward of the shoulders, taking up the tape at this point, has the effect of causing the collar to snugly fit in front, as well as in back, and this is aided by the flexibility of the collar.

before referred to. However, there may be a tendency with a collar such as described for the points to be too soft, and I prefer to stay them by stiffening material 8, inserted 5 along the edge of the collar adjacent to the point thereof and along the gore and free edge, extending only a couple of inches back of the point, leaving the rest of the collar unstiffened.

10 Having thus described my invention what I claim, and desire to secure by Letters Patent is:—

15 1. A coat having the material of its body portion extending upwardly at the neck to the fold of the collar and stiffened at the fold line, a tape extending around the collar opening so formed and continuing to the skirts of the coat, and a collar of a single thickness unstayed at the rear and attached 20 to the neck opening of the body portion.

25 2. A coat having the material of its body portion extending upwardly at the neck to the fold of the collar and stiffened at the fold line, a stay extending around the collar opening so formed and continuing to the skirts of the coat, and a collar unstayed at the rear and attached to the neck opening of the body portion, and having stiffeners located adjacent to and on both sides of the points of the 30 collar at the edge thereof.

35 3. A coat having around the body opening thereof a tape extending around the neck to the skirts thereto and concealed between the outer coat material and the lining of said coat.

In testimony whereof I hereunto affix my signature.

SAMUEL SISKIN.
